(57) **CLAIM**

I claim the ornamental design for a chandelier, as shown and described.

DESCRIPTION

FIG. 1 is a perspective view of a chandelier, showing my new design;

FIG. 2 is a front elevational view thereof, the rear elevational view, left-side elevational view, and right-side elevational view all being mirror images thereof;

FIG. 3 is a top plan view thereof; and,

FIG. 4 is a bottom plan view thereof.

The broken lines showing suspended lamps in FIG. 1 are included for the purpose of illustrating the invention in use, and form no part of the claimed design.
